UNITED STATES PATENT OFFICE

103,214

DESIGN FOR A SHOE

Charles H. Caldwell, Brockton, Mass., assignor to
Geo. E. Keith Company, Campello, Mass., a
corporation of Massachusetts

Application December 24, 1936, Serial No. 66,737

Term of patent 3½ years

To whom it may concern:

Be it known that I, Charles H. Caldwell, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design;

Figure 2 is a side elevation showing one side of the shoe of Figure 1; and

Figure 3 is a side elevation showing the other side of the shoe of Figure 1.

The essential feature of the invention resides in the arrangement and combination of lines of stitching and rectangular punched holes in the material of which the vamp and quarter are made. As the design is applicable to shoes of various shapes and styles the representation of shoe is merely conventional, for showing an application of the design.

I claim:

The ornamental design for a shoe, as shown and described.

CHARLES H. CALDWELL.
